UNITED STATES PATENT OFFICE

2,190,929

PRINTING PRESS FOUNTAIN

Herbert C. Behrens, Battle Creek, Mich., assignor
to Duplex Printing Press Company, Battle
Creek, Mich.

Application August 16, 1937, Serial No. 159,240

1 Claim. (Cl. 101—365)

This invention relates to improvements in printing press fountains.

This invention relates to printing presses and particularly to fountains therefor. It relates particularly to fountains of the type in which a fountain roller is supplied for bringing up ink in which a blade is supplied for removing the surplus. This blade is made adjustable at various points along its length so that the amount of ink brought up for any given column on the matter being printed may be controlled individually. Heretofore several types of adjustment have been used. The simplest one comprises a series of screws which bear down against the blade which is resilient and biased in opposition to the screws. By turning any one screw down it is possible to regulate the spacing of the blade and the roller to control the amount of ink taken up at that point on the roller.

20 In this type of adjustment, it is not practical to provide screws capable of extremely fine adjustment because the force exerted by the screws limits the number of threads per inch and wear which might be occasioned upon finer screws 25 would eventually interfere with the operation of the device. In this type of adjustment the screws are ordinarily adjusted by reaching in to the individual screws on the blade to effect the adjustment. This is inconvenient and it is desirable to have means for adjusting the screws 30 located at a point remote from the screws such as the end of the roller. Remote control of these screws has been accomplished through the use of bevel gears or worm gearing on the screws operated by rotatable shafts extending out to the end of the roller. These devices are impractical and require considerable skill and experience in operation because of the fact that in the rods employed considerable twisting occurs before the 35 rotation of the rod operates the gearing. The amount of this twisting varies with the length of the rods so that it is necessary for an operator to take this into account when adjusting the fountain. More rotation of the rod is required 40 for adjusting the screws at the center of the roller than is required for those at the end of the roller to obtain the same adjustment, and until an operator learns by experience the variations involved, it is most difficult to obtain a satisfactory 45 adjustment. It is obvious that due to lack of space and the expense involved, it is not practicable or desirable to use rods which will not twist on rotation.

The objects of this invention are:

55 First, to produce fountain controlling means

which eliminate the difficulties above referred to.

Second, to produce such a device in which the fountain blade is adjusted from a remote point such as the end of the fountain roller.

Third, to provide such a device which is simple 5 and positive in operation and may be made most inexpensively.

Fourth, to produce such a device in which extremely light connecting members may be employed and in which a given amount of adjustment may be made at any point on the blade by a given manipulation of the remote adjusting mechanism.

Fifth, to provide such a device in which extremely fine adjustments may be effected. 15

Further objects and advantages pertaining to details and economies of construction and operation will appear from the description to follow. The invention is pointed out in the claim. Preferred embodiments of my invention are illustrated in the accompanying drawing, in which:

Fig. 1 is a broken front plan view of a printing press inking fountain embodying my invention.

Fig. 2 is a detail sectional view taken on line 25 2—2 of Fig. 1.

Fig. 3 is a detail sectional view of a different form of my invention.

Fig. 4 is a front plan detail view showing the invention of Fig. 3. 30

Fig. 5 is a front plan view of a still different form of my invention.

Referring to Figs. 1 and 2 of the drawing, 1 is a fountain inking roller having a spring blade 2 which is conventional. This blade is a spring 35 blade and the resiliency of the blade is such that the blade tends to move away from the roller when unrestrained. The roller is mounted in suitable bearings 3 which have a frame 4 supporting the bearings and blade. Disposed along 40 the blade, a blade bar 5 is provided carrying a plurality of bearings 6 having mounted therein the plungers 6! which are slidably mounted for axial movement in said bearings. The plungers 6! engage the blade at spaced points and pressure 45 exerted on the blade by the plungers varies the spacing between the blade 2 and the roller 1.

Pivoted to the blade bar 5 are a plurality of cams 7 in the form of levers 8 having projecting plunger engaging arms 9. Suitable pivots 10 are 50 provided for these cams and the cams are so disposed that if they are pivoted in a counterclockwise direction as viewed at the left of Fig. 1, pressure is exerted to force the blade 2 closer to the roller 1.

A plurality of nuts 11 are provided and wires 12 screw threaded as at 13 to engage the nuts 11 are provided. These wires are attached pivotally each to a cam 7 at a point 14 which is spaced 5 from the pivot of the cam. It will be noted that if tension is exerted on these wires 12 or tension members, the tendency is to urge the cam 7 toward the plunger 8 to force the blade 2 toward the roller 1. If the tension is released, the spring 10 of the blade 2 tends to take up any lost motion and the wires or tension members 12 are kept 15 under tension at all times. The nuts 11 are located on a suitable board or bracket 15 and are provided with fixed bearings 16 which are so disposed that a rotation of the nut 11 on the fixed bearing 16 will exert tension on the tension member or wire 12. It will be apparent that all of the wires 12 may extend to one end of the roller 1 or that the wires may extend to both ends as 20 is indicated in Fig. 1. All of the adjusting means are thus conveniently located so that it is unnecessary to reach in along the blade to effect adjustment. It will be apparent, too, that by properly proportioning the cams 7 it is possible 25 to obtain a very fine adjustment of the plungers 61 and that it is possible to employ very fine screw threads as at 13 on the rods 12 to permit extremely fine adjustment of the blade.

In the form of invention shown in Figs. 3 and 30 4, a blade bar 104 is provided. Cams 107 are pivoted on pivots 110 in a manner similar to the cams 7 in the form of invention shown in Figs. 1 and 2. The cams 107 differ from the cams 7 in that a rounded surface 109 is provided for 35 adjusting the blade. An equalizer pad or block 17 is provided for each cam. These equalizer pads are spaced along the blade and tend to equalize the pressure exerted by rotation of the cams 107. Tension members or wires 112 are 40 provided and by exerting tension on the members 112, the cams 107 are rotated so that the blade 102 is forced downwardly against its spring action toward the roller 101.

In the form of invention shown in Fig. 5, the 45 cam 207 which is substantially identical with the cam 107 is mounted on the blade bar 204 with a

pivot 210. The rounded surface 209 of this cam 207 works directly on the spring blade 202 instead of through an equalizer pad or block such as the equalizer pad or block 17 of Figs. 3 and 4. A tension member 212 is provided and the exertion of tension on the tension member or wire 212 rotates the cam 207 forcing the blade 202 downwardly. 5

In the form of invention shown in Figs. 3, 4 and 5, the means for exerting tension on the 10 tension members may be identical with the means shown in Figs. 1 and 2.

Having thus described my invention, what I claim as new and desire to secure by Letters Patent is:

In a printing press having a fountain roll and a spring blade therefor having a roll engaging edge extending longitudinally of the roll and adapted to be adjusted at different points along its length, the combination of a plurality of cams 20 spaced from one another along said blade each pivoted adjacent said blade on an axis perpendicular to the roll engaging edge of the blade and in operative relation thereto to move a portion of the blade in opposition to the spring of the blade on pivoting of the cam whereby the pivoting of the cam adjusts that portion of the blade adjacent said cam, a plurality of tension members extending along the roll to the end thereof each having one end pivotally connected directly to one of said cams at a point spaced from its pivot, having its free end at the end of the roll screw threaded to engage a nut, a plurality of nuts each in direct screw threaded engagement with the free end of a tension member, and a panel adjacent the end of the roll having a plurality of thrust bearings one for each of said nuts disposed to hold said nuts against movement from the end of said roll along the roll, whereby screwing of a nut on a tension member and against its thrust bearing will exert tension on the cam to which the tension member is connected to turn it about its axis in opposition to the spring of the blade to adjust the position of the blade. 25 30 35 40 45
